UNITED STATES PATENT OFFICE.

LUTHER G. TURNER, OF NEW YORK, N. Y., ASSIGNOR TO THE TURNER & SEYMOUR MANUFACTURING COMPANY, OF TORRINGTON, CONNECTICUT.

DESIGN FOR AN UMBRELLA OR PARASOL HANDLE.

SPECIFICATION forming part of Design No. 20,747, dated May 19, 1891.

Application filed April 10, 1891. Serial No. 388,412. Term of patent 7 years.

To all whom it may concern:

Be it known that I, LUTHER G. TURNER, of New York, in the county and State of New York, have invented and produced a new and original Design for Umbrella and Parasol Handles, of which the following is a specification.

The accompanying drawing represents the handle in side elevation.

- 10 The leading features of my design are a spiral thread forming a winding for the straight portion of the handle, a ring passing through an eye at one end of the handle, the said ring presenting a continuous interior surface and an exterior surface of spiral threads, and a bow at the periphery of the ring.
- 15 A represents the straight portion of the handle having at its ends the bands a a' . At one end of the straight portion of the handle there is an eye B, through which the ring

portion C of the handle extends, the said ring portion C having a smooth interior surface c and an exterior surface consisting of a spiral thread c' , which appears to emanate from the smooth portion of the ring at one edge and vanish within it at the opposite edge. The spiral thread a^2 upon the portion A of the handle presents a series of closely-arranged coils, while the spiral thread c' on the ring portion presents a series of partial coils spaced apart. The spiral threads a^2 and c' are represented as a series of fine threads spaced apart, giving the whole exterior surface a frosted or milled appearance. 35

What I claim is—

The design for an umbrella or parasol handle, as herein shown and described.

LUTHER G. TURNER.
